UNITED STATES PATENT OFFICE.

ORACE V. STUBBS, OF BUDA, TEXAS.

BOLL-WEEVIL EXTERMINATOR.

1,269,234.

Specification of Letters Patent. Patented June 11, 1918.

Application filed June 30, 1917. Serial No. 177,848.

To all whom it may concern:

Be it known that I, ORACE VIRGIL STUBBS, a citizen of the United States, residing at Buda, in the county of Hays and State of Texas, have invented certain new and useful Improvements in Boll-Weevil Exterminators; and I do hereby declare the following to be a full, clear, and exact description of the invention, such as will enable others skilled in the art to which it appertains to make and use the same.

This invention relates to a machine for exterminating boll weevils and the primary object of the invention is to provide a machine of this type employing air suction for drawing the boll weevils and infected squares into a suitable retaining box from which the weevils and infected squares may be removed for destruction and further to provide a pair of hingedly mounted spring controlled plates which ride over the surface of the ground alongside the rows of plants for eliminating to a great extent the drawing of loose dirt upwardly into the machine by the air suction.

A further object of this invention is to provide means for adjusting the vertical position of the hingedly mounted spring controlled plates so that when the machine is not in use, these plates may be moved upwardly out of the ground engaging position.

Another object of the invention is to provide a machine as specified, the main body of which forms an air suction chamber which passes over the cotton plants during the travel of the machine, and while over the plants subjects them to an air suction from a rotary fan which is positioned upon the top of the main body and which is operated through the medium of a plurality of gears, by the travel of the machine and further to provide a removable weevil infected square receiving member which is positioned alongside of the suction fan, so that the weevils and infected squares drawn upwardly by the fan action will be guided into the retaining box or compartment from which they may be removed through an ordinary door and also to provide a novel form of rotary valve for cutting off the passage of communication between the air suction chamber and the weevil retaining compartment when it is desired to remove the compartment, and which valve is constructed for forming a guide to guide the weevils

and squares into the compartment when the latter is in use.

With the foregoing and other objects in view, this invention consists in such novel features of construction, combination and arrangement of parts as will be hereinafter more fully described, illustrated in the accompanying drawings and claimed.

In describing the invention in detail reference will be had to the accompanying drawings wherein like characters designate like and corresponding parts throughout the several views, and in which:

Figure 1 is a side elevation of the improved boll weevil exterminator,

Fig. 2 is a top plan view of the exterminator with the seat removed,

Fig. 3 is a longitudinal section through the exterminator on the line 3—3 of Fig. 2,

Fig. 4 is a rear elevation of the exterminator,

Fig. 5 is a vertical transverse section through the exterminator on the line 5—5 of Fig. 2,

Fig. 6 is a detail bottom plan of a part of the mechanism for controlling the operation of the suction means of the exterminator,

Fig. 7 is a detail view of the gearing for controlling the suction mechanism of the exterminator,

Fig. 8 is a detail section through the hub of the supporting wheel of the machine,

Fig. 9 is a section on the line 9—9 of Fig. 2, and

Fig. 10 is a detail perspective of the valve construction controlling the passage of the boll weevils and infected squares into the retaining receptacle, showing the latter in dotted lines. Fig. 11 is a detail longitudinal section through a part of Fig. 10.

Referring more particularly to the drawings, 1 designates the supporting axle of the boll weevil machine which is of the arch type and has the wheel carrying spindles 2 formed upon each end thereof. The main supporting wheels 3 are mounted upon the spindles 2 and are held thereon by U-shaped keys 4 which are seated in key-ways 5 formed in the end of the hub 6 of the supporting wheel 3 and in key-ways 7 which are formed in the ends of the spindles 2. The usual type of dust cap 8 is mounted over the end of the hub 6 as clearly shown in Fig. 8 of the drawings. The hubs 6 of the supporting wheels 3 have the driving sprockets 9 mounted thereon, as clearly

shown in Fig. 8 of the drawings, and the usual type of pawl and ratchet structures indicated at 10 is provided for rotating the sprockets 9 upon the forward travel of the machine by the rotation of the wheels 3 and to permit the sprockets to remain stationary for the rearward or reverse rotation of the supporting wheels 3.

Sprocket chains 11 travel about the sprockets 9 and about sprockets 12 which are carried by a shaft 13. The shaft 13 is supported by suitable bearings 14 which have right angularly disposed bearing collars 14' formed thereon that are mounted upon the rear end of the bracing rod structure 15. The bracing rod structure 15 is substantially U-shaped, and is attached by means of suitable attaching straps 16 to the top of the main body of the machine. The rod structure has a tongue 18 of the usual construction connected to the center of the bight portion 19 thereof as clearly shown in Fig. 2 of the drawings and suitable brace rods 20 are attached to the tongue 18 as shown at 21 and to the top of flanges 22' formed upon the lower edges of the sides 22^a of the main body of the machine as shown at 22. The usual type of draft trees indicated at 23 are carried by the tongue 18 for the purpose of hitching the draft animals thereto. A reinforcing collar 18' is mounted about the inner end of the tongue 18.

The main body of the device forms a suction chamber 17 which has its bottom open, while the front side 24 is provided with a cut out portion 25 which allows the device to pass over growing cotton plants. Positioned within the suction chamber 17 directly in rear of the opening 25 is a plant agitator 26 which is mounted upon a suitable shaft or rod 27 and comprises a plate 28 having depending sides 29 which plate strikes the cotton plants and bends them over, causing them to fly up when they are disengaged by the agitator structure 26 and thereby thoroughly shaking the plants as well as striking the plant next thereto, to be engaged by the agitator and agitating this plant providing double agitation to the plants for shaking boll weevils, other insects and infected squares therefrom. The rear wall 30 of the main body is provided with an opening 31 that aligns with the opening 25. The rear wall of the suction chamber is attached to the side walls 22^a and the top 32 by means of flanges 30^a formed upon the edges of the rear wall which flanges abut and are attached to the side walls and tops by means of bolts or rivets 30^b.

The suction chamber has communication through an opening 33 formed in the top 32 of the main body with the interior of the fan casing 34 which is supported by a suitable support 34'. The support 34' is constructed of sheet metal or analogous mate-

rial, and its sides are curved, and converge slightly as they extend upwardly, to form a tubular communication between the interior of the fan casing and the interior of the body of the boll weevil exterminator. The support 34' may be soldered to the fan casing and top 32 to provide an air tight connection. A rotary suction fan 35 is mounted within the casing 34 for creating an air suction upwardly through the suction chamber 17 and into the compartment 36 of the removable insect receiving receptacle 37. The fan 35 is mounted upon a shaft 38 which extends longitudinally through the casing 34 and is supported by suitable bearings 39 and 39'. The bearing 39' has its ends bent substantially at right angles to the main body thereof as shown at 39^a and the resiliency of these angled ends cause them to frictionally grip the interior of the circular casing 34 and hold the bearing 39 in place. The shaft 38 has a gear 40 mounted thereon which meshes with a gear 41. The gear 41 is mounted upon a shaft 42 which extends along the upper surface of the top 32 and is rotatably supported by suitable bearings 43. The shaft 42 has a gear 44 slidably mounted thereon and held in place by means of a set screw 45 which extends through the elongated hub 46 formed upon the gear. The gear 44 is provided for meshing with either the outermost set of gear teeth 47 or the innermost set of gear teeth 48 which are formed upon one face of the gear 49 for regulating the speed of rotation of the shaft 42, as desired.

The gear 49 is mounted upon the shaft 13 for independent rotation with respect thereto and it has a clutch section 50 formed on the hub thereof which is adapted for coaction with a clutch section 51. The clutch section 51 is carried by a sleeve 52 upon which is mounted a disk 53. The sleeve 52 is feathered upon the shaft 13. A spring 54 is coiled about the shaft 13 and one end of the spring is connected to the shaft while the other end engages the disk 53 for holding the clutch section 51 into engagement with the clutch section 50 for rotating the shaft 49 by the rotation of the shaft 13. The clutch section 51 is moved out of engagement with the clutch section 50 through the medium of a pivotally mounted angled lever 55 which has a roller 56 carried by one end of the same. The roller 56 engages one surface of the disk 53, so that upon rocking movement of the angled lever 55 by the longitudinal movement of the rod 57 it will force the clutch section 51 out of engagement with the clutch section 50 and arrest rotation of the gear 49 from the rotation of the shaft 13. The rod 57 is connected to a lever 57' which is pivotally connected to the front 24 of the main body.

The receptacle or casing 37 is provided

with a suitable door 60 out of which the insects and infected squares are dumped and it is detachably connected to the fan casing 34 by a overlapping metal strip 61 that overlaps the edge of the rounded portion 62 of the casing. The casing 37 is held in place by, and it rests upon a suitable spring or resilient plate 64 which is suitably connected to the top 32 and has an upstanding portion 65 formed thereon for limiting the forward movement of the outer rectangular retaining portion 66 of the casing 37. The plate 64 projects rearwardly and upwardly from the rear end of the casing 37, as clearly shown at 68 in Figs. 1 and 3 of the drawings to provide means for holding the receptacle 37 in place and for guiding its disconnecting movement. The plate 64 has legs 64^a formed thereupon which are fastened in any suitable manner to the top 32 of the main body of the boll weevil exterminator. The circular portion 62 of the casing 37 has a rotary valve member 70 mounted therein. The valve member 70 comprises a cylindrical member 71 which has a handle 72 connected thereto for rotating the same, which handle projects through a slot 72^a formed in the circular portion 62. The cylindrical member 71 is provided with a cut out portion 73 which is adapted for registration with the mouth of the rectangular portion 66 of the casing 37 for permitting communication between the circular and rectangular portions of the casing. The circular member 71 has a guiding plate 74 mounted therein which extends throughout the entire length of the cylindrical member and at an incline, as clearly shown in Fig. 10 of the drawings, the forward end of the plate being secured to the inner surface of the forward end of the cylindrical valve member 71, and extending upwardly therefrom so as to properly guide boll weevils and infected squares upwardly through the cut out portion 73 for passage into the rectangular portion 66 when the valve is open. The cylindrical valve member 71 has communication with the interior of the fan casing 34 so that the current of air generated by the fan will pass upwardly through the main body 17, the fan casing 34, into the rotary cylindrical valve member 71 wherein it will be deflected or guided by the arcuate plate 74 into the substantially rectangular portion 66 which receives and retains the boll weevils and infected squares until they are removed therefrom through the door 60. The circular portion 62 of the casing 37 is provided with an opening 62^a which permits escape of air therefrom, when the valve member 70 is in a closed position.

The substantially rectangular portion 66 of the receptacle 37 has an opening 76 formed in the top of the same which is screened by a suitable screen 77 so as to permit the air to pass outwardly out of the cas-

ing and prevent the insects from passing out of the casing. A guard plate 78 is positioned over one side of the opening 76 for deflecting the air from the seat 79 of the device so that the air blast will not strike the operator of the machine. A pair of plates 80 and 81 are adjustably carried within the main body and they are provided with slots 83 in which guiding members 84 travel. The guiding members 84 are carried by the sides 75 22^a of the main body.

Runners or angled plates 85 are hingedly connected as shown at 86 to the lower edges of the vertically movable plates 80 and 81. The angled plates 85 include horizontally positioned portions 87 which extend inwardly toward the center of the casing 17 and are provided for moving along each side of a row of cotton plants to prevent the sucking of loose dirt upwardly into the casing or 85 receptacle 37 by the action of the fan 35. Contractile springs 88 are connected to the horizontal portions 87 and to angle iron bars 110 for holding the horizontal portions in their normal position and for returning them 90 to their normal position after they have been moved outwardly as shown in dotted lines in Fig. 5 of the drawings to allow them to pass a rock, root, stump or the like during the travel of the boll weevil exterminating 95 machine. The springs 88 have their upper ends connected to the angle iron bars 110 which are attached to the inner surfaces of the vertically movable plates 80 and 81. The angle iron bars 110 project below the lower 100 edges of the vertically movable plates 80 and 81 and form stops for limiting the upward movement of horizontal portions 87 of the angle plates 85.

Bars 90 are connected as shown at 91 to 105 the vertically movable plates 80 and 81 and they project upwardly through the top 32. The upper ends of the bars 90 are in turn connected to bars 92 which extend downwardly along the outer surfaces of the sides 110 of the main body and are connected as shown at 93 to segments 94. The segments 94 are mounted upon the ends of the shaft 27. A hand lever 95 is mounted upon the shaft 27 for rocking the same and for rocking the 115 segments 94 to raise or lower the plates 80 and 81 depending upon the direction in which the lever is moved. The lever 95 has the usual type of dog mechanism 96 carried thereby which coacts with a quadrant 97, 120 for holding the lever 95 in various adjusted positions. A quadrant 97 has collars 97^a formed upon the end thereof which collars are mounted upon the rearwardly extending side or legs 15^a of the U-shaped member 15. 125

Suitable braces 98 extend diagonally from the axle 1 near the spindle ends of the same to the rearwardly extending legs of the substantially U-shaped brace 15.

In the operation of the improved ma- 130

chine; when entering a field, for exterminating boll weevils and other insects which might infest the cotton plants, the gear 44 is first shifted so that it will mesh with either the set 47 or the set 48 of teeth, depending upon the speed of rotation of the fan 35 desired, and after this adjustment has been made, the plates 80 and 81 are lowered so that the horizontal portions 87 of the 5 hinged angle plates 85 will ride over the surface of the ground alongside the rows of plants, and the lever 72 is operated for permitting communication between the circular and substantially rectangular portions 10 of the casing 37. The air suction generated by the rotation of the fan 35 will pass upwardly through the suction chamber 17, into the circular portion 62, from thence into the rectangular portion 66 and outwardly 15 through the opening 76, drawing the boll weevils, other insects and infected squares upwardly into the compartment 66. The air suction action of the machine is facilitated in removing the insects and infected squares 20 from the plants by the operation of the agitator 26 which will strike the plants and bend their tops downwardly, shaking them and releasing them so that they will fly back to their normal position which will thoroughly 25 shake the plants and agitate the plants next thereto, facilitating in the shaking of the boll weevils and infected squares from the plants. The boll weevils and infected squares as well as other insects 30 may be removed from the receptacle 37 when desired and destroyed in any suitable manner.

From the foregoing description taken in connection with the accompanying drawings, the advantages of construction and of the method of operation of the improved boll weevil exterminator will be readily apparent to those skilled in the art to which this invention appertains and, while in the foregoing description, the principle of the operation of this invention has been described together with various features of construction, it is to be understood that certain minor features of construction, combination and arrangement of parts may be altered to suit practical conditions provided such alterations are comprehended within the scope of what is claimed.

What is claimed is:—

- 55 1. In a boll weevil exterminator, a housing, means for creating an air suction within said housing, and a pair of plates adjustably carried by the sides of said housing and having their lowermost portions bent inwardly at right angles to the sides of the housing for preventing loose dirt from being drawn upwardly into the housing.
- 60 2. In a boll weevil exterminator, a housing forming a suction chamber, means for creating an air suction through said chamber,

plates adjustably carried by the sides of said housing for vertical adjustment with respect thereto, plates hingedly connected to the lower edges of said vertically adjustable plates for adjustment therewith, said hinged plates having their lower portions bent at right angles to the sides of the housing for preventing air suction from drawing loose dirt upwardly into the housing.

3. In a boll weevil exterminator, a housing forming a suction chamber, means for creating an air suction through said chamber, plates adjustably carried by the sides of said housing for vertical adjustment with respect thereto, plates hingedly connected to the lower edges of said vertically adjustable plates for adjustment therewith, said hinged plates having their lower portions bent at right angles to the sides of the housing for preventing air suction from drawing loose dirt upwardly into the housing, and springs connected to said hinged plates and said adjustable plates for holding the lower angled portions of the hinged plates in a substantially horizontal plane.

4. In a boll weevil exterminator, a housing forming a suction chamber, means for creating an air suction through said chamber, plates adjustably carried by the sides of said housing for vertical adjustment with respect thereto, plates hingedly connected to the lower edges of said vertically adjustable plates for adjustment therewith, said hinged plates having their lower portions bent at right angles to the sides of the housing for preventing air suction from drawing loose dirt upwardly into the housing, means for holding said lower bent portions in a horizontal position, and means for limiting the upward hinged movement of said hinged plates.

5. In a boll weevil exterminator, a housing forming a suction chamber, supporting wheels carried by said housing, means for creating an air suction upwardly through said housing, a receptacle carried by the housing for receiving insects and infected squares which are drawn upwardly by the air suction within the housing, a plate pivotally mounted within said housing and adapted to strike cotton plants upon passage of the housing thereover for agitating the plants to shake boll weevils and infected squares from the plants, plates adjustably carried by the sides of said housing for vertical adjustment, angle plates hingedly connected to the lower edges of said adjustable plates for vertical adjustment therewith, said angle plates having their lower portions bent to normally lie in horizontal planes for riding upon the surface of the ground alongside a row of plants, and springs connected to the horizontal portions of said hinged angle plates for normally holding them in horizontal position, and means con-

nected to said vertically adjustable plates for adjusting them in unison.

6. In a boll weevil exterminator, a housing forming a suction chamber, supporting 5 wheels carried by said housing, means for creating an air suction upwardly through said housing, a receptacle carried by the housing for receiving insects and infected squares which are drawn upwardly by the 10 air suction within the housing, a plate pivotally mounted within the housing and adapted to strike cotton plants upon passage of the housing thereover for agitating the 15 plants to shake boll weevils and infected squares from the plants, a pair of hinged plates adjustably carried by the sides of said

housing and having their lowermost portions bent inwardly at right angles to the sides of the housing for preventing loose dirt from being drawn upwardly into the 20 housing, means connected to said hinged plates for normally holding their lower angled portions in a substantially horizontal plane, and means for limiting the upward movement of said horizontal portions. 25

In testimony whereof I affix my signature in presence of two witnesses.
